UNITED STATES PATENT OFFICE.

THOMAS E. HAYES, OF MILWAUKEE, WISCONSIN, ASSIGNOR OF ONE-THIRD TO
WILLIAM R. CALLAHAN AND ONE-THIRD TO HUGO A. KLEINSTUEBER,
BOTH OF MILWAUKEE, WISCONSIN.

COMBINATION TRAFFIC GUIDE AND TRAFFIC-REGULATING SIGNAL.

Application filed August 7, 1922. Serial No. 580,372.

To all whom it may concern:

Be it known that I, THOMAS E. HAYES, a citizen of the United States, and resident of Milwaukee, in the county of Milwaukee and 5 State of Wisconsin, have invented certain new and useful Improvements in Combination Traffic Guides and Traffic-Regulating Signals; and I do hereby declare that the following is a full, clear, and exact description thereof.

The invention relates to a combination traffic guide and traffic regulating signal. It comprises a device adapted to be located in the middle of streets at street intersections for signalling "Stop" and "Go," the device being positioned close to the level of the pavement, and a guard being provided to protect the mechanism from the wheels of vehicles.

It is the object of the invention to provide combined means for signalling to regulate traffic, and means for guiding traffic at corners. With the signalling devices positioned adjacent the pavement, the drivers of vehicles do not have to look up as has hitherto been the case with control signals of the old type. The signal is continuously illuminated and a single source of illumination is therefore operative for two distinct purposes, namely, for regulating the traffic and guiding it. The provision of a metallic guard prevents all danger of damage to the mechanism. It may be used to advantage in congested places, as between tracks, as it takes up but a minimum of room.

With the above and other objects in view which will appear as the description proceeds, the invention resides in the novel construction, combination and arrangement 40 of parts substantially as hereinafter described and more particularly defined by the appended claims, it being understood that such changes in the precise embodiment of the herein disclosed invention may be made 45 as come within the scope of the claims.

In the accompanying drawing, is illustrated one complete example of the physical embodiment of the present invention constructed according to the best mode so far devised for the practical application of the principles thereof.

Figure 1 is a central vertical section of the device on the line 1—1 of Figure 2.

Figure 2 is a plan thereof.

A rectangular dished base 10 is imbedded 55 in the pavement 11, and is provided with an upwardly extending flange 12 spaced inwardly from a peripheral band 13. Immediately adjacent band 13 and resting on base 10 at the edge thereof, is a grooved ring 14 60 receiving the edges of a metallic guard 15 which is rounded at its top and provided with substantially vertical sides cut away to form openings 16. The guard conforms to the rectangular shape of base 10, and is 65 curved at the corners. The openings 16 extend almost the entire width of the guard. The top of the guard is cut away to form apertures 17. A glass globe 18 is encased by 70 the guard; it is similar in shape and spaced slightly along its entire surface from the inner surface of the guard. The lower edge of the globe is received in a gasket 19 immediately adjacent ring 14, whereby it is securely retained in position.

A box-like member is housed within the globe positioned on base 10. It is rectangular in horizontal outline, and provided with glass windows 20 and 21, in each of four side faces. Immediately above the side faces 80 is an inclined face having a window 22 therein. Means for illuminating the box are provided, pipe 23 assisting in the performance of this function, the pipe extending thru the center of the base and directed 85 upwardly to the bottom of the box. Window 20, when illuminated, signals "Stop," window 21, when illuminated, signals "Go," and window 22 signals "Traffic change." The entire device is small in vertical dimension and occupies a minimum of room. Thus it may be used in congested places, as between tracks. The guard 15 protects all 90 parts from damage. The device is adapted to be located in the middle of streets at 95 street sections, and therefore comes immediately within the range of vision of the driver of the car, making it unnecessary for him to look up to read the signal exhibited. Thus it does not interfere with the normal 100 operation of the car and is entirely safe. As either the "Stop" or the "Go" signal is exhibited at all times in a particular direction thru the openings 16, a guide light is at all times displayed indicating the point 105 at which a turn is to be made. Thus the device performs the twofold function of guiding and controlling traffic. The mechanism

whereby the "Stop" and "Go" signals are exhibited is well known.

Applicant does not limit himself to the specific box structure illustrated. If desired 5 on all four faces of the box, the word "Stop" may be exhibited above and the word "Go" below.

I claim:

1. In a device of the class described, the 10 combination of a low mushroom shaped metallic guard adapted to be positioned adjacent the level of the pavement and having openings therein adjacent the level of the pavement, and means for exhibiting thru 15 said openings the words "Stop" and "Go" immediately adjacent to the level of the pavement.

2. In a device of the class described, a low mushroom shaped metallic guard having 20 openings therein, a stationary housing within said guards and windows in the sides of said housing elongated to make visible thru said openings the words "Stop" and "Go".

3. In a device of the class described, a low 25 mushroom shape metallic guard having openings therein, a glass globe within said guard, a stationary housing within said globe and windows in the sides of said housing adapted to be illuminated to exhibit the 30 words "Stop" and "Go."

4. In a device of the class described, the combination of a low guard having four

sides which are straight in plan view, each of said sides having an elongated opening therein, said guard having a low convex top 35 and a means within said guard for revealing through said openings "Traffic change", "Stop" and "Go" signals.

5. In a device of the class described, the combination of a low metallic guard having 40 four sides which are straight in plan view, each of said sides having an elongated opening therein, a low convex roof for said guard, a glass globe within said guard conforming to the shape of said guard and 45 spaced slightly from said guard, and means for displaying through said openings "Traffic change", "Stop" and "Go" signals.

6. The combination of a low metallic guard having four sides which are straight 50 in plan view, each of said sides having an elongated opening therein, said guard having a low convex roof, a glass globe within said guard conforming to the shape thereof, a box-like housing within said globe having 55 four faces, each of said faces having windows on which the words "Traffic change", "Stop" and "Go" are visible.

In testimony that I claim the foregoing I have hereunto set my hand at Milwaukee, 60 in the county of Milwaukee and State of Wisconsin.

THOMAS E. HAYES.
